UNITED STATES PATENT OFFICE.

IRVING R. VERSOY, OF NEW HAVEN, CONNECTICUT, ASSIGNOR TO THE BERGER BROTHERS COMPANY, OF NEW HAVEN, CONNECTICUT.

CORSET.

Application filed June 30, 1925. Serial No. 40,653.

This invention relates to corsets or girdles, and more especially to a garment of this type which is designed to properly support the abdomen of the wearer and to correct the posture, and while it is adapted to support and compress certain portions of the body, at the same time it is so made that the utmost freedom of movement will be permitted the body of the wearer. In the past, some difficulty has been experienced in providing a garment of this character which, while sufficiently flexible or elastic to permit the desirable freedom of movement, will at the same time be sufficiently rigid and non-elastic to give the required support to the abdomen so that the weight of this part of the body will be properly carried by the bony structure of the hips, known as the pelvic girdle. My invention obviates these disadvantages in prior garments chiefly by placing an inelastic portion or girdle at that portion of the garment which embraces the pelvic girdle, and elastic sections above and below the central girdle so that while the pelvic region will be properly compressed and supported, freedom of movement will be permitted above and below this section.

One object of my invention, therefore, is to provide a novel form of corset which, while giving proper support to the abdomen and causing the weight of this part of the body to be carried by the hip bones, will provide for the utmost freedom of movement above and below this portion of the body.

A further object of my invention is the provision of a corset wherein an inelastic section is provided to embrace the pelvic region, and elastic sections extending substantially throughout the width of the garment above and below this section.

A still further object of my invention is the provision of a novel and improved method of joining the elastic sections of the garment to the inelastic portion thereof.

To these and other ends, the invention consists in the novel features and combination of parts to be hereinafter described and claimed.

In the accompanying drawings:

Fig. 1 is a front elevational view of a

corset embodying my invention, as it appears when upon the body of the wearer;

Fig. 2 is an inside view of the corset when open and extended;

Fig. 3 is a sectional view on line 3—3 of Fig. 2;

Fig. 4 is a view similar to Fig. 1 showing a front lace corset embodying my improvements, and

Fig. 5 is an inside view of the front lace corset shown in Fig. 4 when open and extended.

The garment which I have selected to illustrate and describe as embodying my invention may, as illustrated, be adapted to either the front or back lace type of corset, that is, the garment may be made in two sections, as shown in Fig. 2, which are laced together at the back and secured by clasps at the front, or as shown in Fig. 5, the corset may be made in one piece, the free edges meeting and being laced together at the front. It will, of course, be obvious that other modifications may be resorted to as concerns the fastening of the free edges of the garment, for if desired, it may be made without laces.

As shown in Figs. 1 and 2, the corset consists of rear stay sections 10 and 11 secured by the laces 12 and front stay sections or busks 13 and 14, provided with clasps 15 and 16 by which the meeting edges of the garment may be connected. It will be noted that the rear stay sections are somewhat longer than those at the front of the garment and while such construction is preferable, changes may be made in the relative lengths of these two parts to suit the individual wearer.

The lower ends of the long stay sections in the rear of the garment are adapted, when the corset is in place, to engage below the buttocks of the wearer and thus prevent the garment from tending to work upwardly on the body out of its proper position. The front stay sections being relatively rigid, especially at those portions to which the clasps are attached, are preferably of the proper length so that they do not extend downwardly in front of the lower limbs and interfere with the assumption of a sitting position by the wearer.

Secured to the front and rear stay sec-

tions is a central girdle portion consisting, as shown, of inelastic gores or sections 17, 18, 19 and 20. Preferably, this girdle portion will be wider at the back adjacent the rear stays than at the front adjacent the busks. This is provided, as shown, by tapering the sections of this part of the garment and especially the lower edges thereof. It will be understood that the sections 10, 10 11, 13 and 14 are formed of inelastic material as well as the sections of the central girdle, so that there will be an entire embracing structure or girdle of inelastic material about the pelvic region.

15 The position of the garment in respect to the pelvis is shown in Fig. 4, wherein the ilium is shown at 21, the pubes at 22 and the ischium at 23. While this is shown in connection with the front lace type of garment, 20 it will be understood that the garment shown in Figs. 1 and 2 is designed to occupy the same relative position on the body of the wearer. It will be apparent from this, however, that the abdomen will be supported by 25 an inelastic band or girdle so positioned as to cause the weight of this part of the body to be carried by the hips, and that the organs in the lower part of the abdomen will be pressed upwardly as is desirable, and which 30 is a function which cannot be performed properly by an elastic garment.

The front and rear stay sections preferably extend above the central inelastic band or girdle, and to the upper ends of these sections are secured elastic sections 24 and 25. The lower edges of these elastic sections are secured to the central band by a butt joint which will be more fully described herein-after. This joint is preferably substantially 40 at the waist-line of the wearer so that the elastic portion of the garment extends slightly above this line and provides some freedom of movement at this part of the garment.

45 Similarly, the lower ends of the front and rear stay sections extend below the central band, and between these extending ends are inserted elastic sections 26 and 27, which are connected to the front and rear stay sections 50 and also secured to the central band at the meeting edges of these parts by means of the butt joint shown especially in Fig. 3. As shown in this figure, the meeting edges of these two parts of the garment are bound 55 by tape, or the like, as at 28 and 29, and the edges abutted closely together and securely stitched in zig-zag fashion, the thread passing over the joint between the two sections and entering first one and then the other. 60 It will be apparent that this provides a flat joint or seam between the two parts and obviates the extra thickness or bulkiness which would be present if the adjacent edges of the two sections were lapped and then 65 sewed. At the same time, the garment pos-

sesses a neat and attractive appearance and is, of course, more comfortable to wear.

Hose supporters 30, 31, 32 and 33 may be secured to the lower edge of the garment, the supporters 31 and 32 preferably being 70 secured at the lower end of two of the stay sections while the front supporters 30 and 33 are secured at the corners of the elastic sections where they are reinforced by the edge binding 34 and 35, which extends over 75 the front edges of the sections 26 and 27 and below the front busk sections.

The front-lace type of garment shown in Figs. 4 and 5, is constructed in substantially the same manner as has already been set forth in detail in connection with the garment shown in Figs. 1 to 3, except that the rear stay sections 10^a and 11^a are joined rigidly together by the section 12^a, and the front busk sections 13^a and 14^a are provided 80 with eyelets 15^a and 16^a through which laces may be passed. It will be noted that the front busk sections are slightly longer than those shown in connection with the back-lace type of garment, and as has already 85 been indicated, this may be preferable in some cases, depending on the individual requirements or measurements of the wearer.

It will be understood that the seams or joints between the central band and the elastic sections of this type of garment are formed in the manner shown in Fig. 3, which 90 has already been described in detail.

It will be observed that in both of the forms shown there is provided an inelastic 100 girdle portion extending substantially from the waistline to the region of the pubic bones, this girdle portion being of substantial width and adapted to confine a large 105 portion of the pelvic region for the purpose described. The upper elastic section extending from the waistline upwardly is preferably quite narrow, being considerably narrower than the lower elastic section, and the latter being preferably somewhat narrower 110 in turn than the inelastic girdle portion. The girdle portion is tapered so as to be narrower at the front than at the back, while conversely the lower elastic section is tapered 115 in the other direction so as to be somewhat narrower at the back than at the front. The front stay sections preferably extend from the top of the upper elastic section down past the inelastic girdle portion to a 120 point intermediate of the upper and lower edges of the lower elastic section, so that a part of the latter extends downwardly beyond the front stays, as shown in Figs. 1 and 4; that is to say, downwardly beyond the region of the pubic bones where the front stay sections come to an end.

While I have shown and described preferred embodiments of my invention, it will be understood that it is not limited to all the 125 details shown, but is capable of modifica- 130

tion and variation within the spirit of the invention and the scope of the appended claims.

What I claim is:

5. A corset comprising front and rear stay sections, a body encircling girdle portion of considerable width constructed of inelastic material and connected to said stay sections, and upper and lower elastic sections adjoining respectively the upper and lower edges of said girdle portion and secured thereto and to the front and rear stay sections, the upper elastic section being disposed substantially at the waist line of the wearer and of less width than the lower elastic section, and the lower elastic section being of substantially less width at the rear of the corset than said inelastic girdle portion. 60
10. A corset comprising a relatively wide inelastic girdle portion encircling the pelvic region of the body and having its upper edge disposed substantially at the waist line, front and rear stay sections extending vertically above and below said girdle portion, and elastic sections secured between the projecting ends of the stay sections at the top and bottom of the girdle portion, said girdle portion tapering toward the front of the garment so as to be narrower at the front than at the back. 65
15. A corset comprising a relatively wide inelastic girdle portion encircling the pelvic region of the body and having its upper edge disposed substantially at the waist line, front and rear stay sections extending vertically above and below said girdle portion, and elastic sections secured between the projecting ends of the stay sections at the top and bottom of the girdle portion, said girdle portion tapering toward the front of the garment so as to be narrower at the front than at the back, and said lower elastic section being correspondingly wider at the front of the garment. 70
20. A corset comprising front and rear stay sections, a body encircling girdle portion of substantial width and of inelastic material connected to said stay sections, and adapted to confine and compress the body from an upper limit located about the waistline to a lower limit located at about the region of the pubic bones, and upper and lower elastic sections co-extensive in length with the girdle section and adjoining respectively the upper and lower edges thereof to provide elastic sections about the waist and the lower portion of the hips of the wearer, said elastic sections being connected at their front and rear edges to the front and rear stay sections respectively. 75
25. A corset comprising front and rear stay sections, a body encircling girdle portion of substantial width and of inelastic material connected to said stay sections, and adapted to confine and compress the body from an upper limit located about the waistline to a lower limit located at about the region of the pubic bones, and upper and lower elastic sections co-extensive in length with the girdle section and adjoining respectively the upper and lower edges thereof to 80 provide elastic sections about the waist and the lower portion of the hips of the wearer, said elastic sections being connected at their front and rear edges to the front and rear stay sections respectively, said front stay sections being shorter than the rear stay sections, and said lower elastic section having a free edge extending downwardly below the front stay sections. 85
30. A corset comprising front and rear stay sections, a body encircling girdle portion of substantial width and of inelastic material connected to said stay sections, and adapted to confine and compress the body from an upper limit located about the waistline to a lower limit located at about the region of the pubic bones, and upper and lower elastic sections co-extensive in length with the girdle section and adjoining respectively the upper and lower edges thereof to 90 provide elastic sections about the waist and the lower portion of the hips of the wearer, said elastic sections being connected at their front and rear edges to the front and rear stay sections respectively, said front stay sections being shorter than the rear stay sections, and said lower elastic section having a free edge extending downwardly below the front stay sections. 95
35. A corset comprising front and rear stay sections, a body encircling girdle portion of substantial width and of inelastic material connected to said stay sections, and adapted to confine and compress the body from an upper limit located about the waistline to a lower limit located at about the region of the pubic bones, and upper and lower elastic sections co-extensive in length with the girdle section and adjoining respectively the upper and lower edges thereof to 100 provide elastic sections about the waist and the lower portion of the hips of the wearer, said elastic sections being connected at their front and rear edges to the front and rear stay sections respectively, said front stay sections being shorter than the rear stay sections, and said lower elastic section having a free edge extending downwardly below the front stay sections. 105
40. A corset comprising front and rear stay sections, a body encircling girdle portion of substantial width and of inelastic material connected to said stay sections, and adapted to confine and compress the body from an upper limit located about the waistline to a lower limit located at about the region of the pubic bones, and upper and lower elastic sections co-extensive in length with the girdle section and adjoining respectively the upper and lower edges thereof to 110 provide elastic sections about the waist and the lower portion of the hips of the wearer, said elastic sections being connected at their front and rear edges to the front and rear stay sections respectively, said front stay sections being shorter than the rear stay sections, and said lower elastic section having a free edge extending downwardly below the front stay sections. 115
45. A corset comprising front and rear stay sections, a body encircling girdle portion of substantial width and of inelastic material connected to said stay sections, and adapted to confine and compress the body from an upper limit located about the waistline to a lower limit located at about the region of the pubic bones, and upper and lower elastic sections co-extensive in length with the girdle section and adjoining respectively the upper and lower edges thereof to 120 provide elastic sections about the waist and the lower portion of the hips of the wearer, said elastic sections being connected at their front and rear edges to the front and rear stay sections respectively, said front stay sections being shorter than the rear stay sections, and said lower elastic section having a free edge extending downwardly below the front stay sections.
50. A corset comprising front and rear stay sections, a body encircling girdle portion of substantial width and of inelastic material connected to said stay sections, and adapted to confine and compress the body from an upper limit located about the waistline to a lower limit located at about the region of the pubic bones, and upper and lower elastic sections co-extensive in length with the girdle section and adjoining respectively the upper and lower edges thereof to 125 provide elastic sections about the waist and the lower portion of the hips of the wearer, said elastic sections being connected at their front and rear edges to the front and rear stay sections respectively, said front stay sections being shorter than the rear stay sections, and said lower elastic section having a free edge extending downwardly below the front stay sections.
55. A corset comprising front and rear stay sections, a body encircling girdle portion of substantial width and of inelastic material connected to said stay sections, and adapted to confine and compress the body from an upper limit located about the waistline to a lower limit located at about the region of the pubic bones, and upper and lower elastic sections co-extensive in length with the girdle section and adjoining respectively the upper and lower edges thereof to 130 provide elastic sections about the waist and the lower portion of the hips of the wearer, said elastic sections being connected at their front and rear edges to the front and rear stay sections respectively, said front stay sections being shorter than the rear stay sections, and said lower elastic section having a free edge extending downwardly below the front stay sections.

In witness whereof, I have hereunto set my hand this 25th day of June, 1925.

IRVING R. VERSOY.
